Primary Examiner — Mary Ann Calabrese(74) *Attorney, Agent, or Firm* — Michael Crilly, Esquire(57) **CLAIM**

The ornamental design for a desktop with stowed legs, as shown and described.

DESCRIPTION

This application is related to concurrently filed, and commonly assigned U.S. Design patent application Ser. No. 29/644,168 entitled Desk now U.S. Pat. No. D879,514 and PCT Application No. PCT/US2018/027701 entitled Desk System, the disclosures of which are hereby incorporated herein by reference thereto.

FIG. 1 is a top right side perspective view for a desktop with stowed legs showing our new design;

FIG. 2 is a bottom right side perspective view thereof;

FIG. 3 is a left side elevation view thereof;

FIG. 4 is a right side elevation view thereof;

FIG. 5 is a front side elevation view thereof;

FIG. 6 is a rear side elevation view thereof;

FIG. 7 is a top plan view thereof;

FIG. 8 is a bottom plan view thereof; and,

FIG. 9 is a fragmentary cross-sectional view taken along line 9-9 in FIG. 8.

The broken lines form no part of the claimed design.
